Primary Examiner — Joseph Kukella

Assistant Examiner — Arva P Adams

(57) **CLAIM**

The ornamental design for a bottle rack, as shown and described.

DESCRIPTION

FIG. 1 is a perspective view of a bottle rack showing my new design.

FIG. 2 is a rear, bottom, and right side perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

Any shading and cross-hatching are not features of the design but are utilized to illustrate the surface contours of the bottle rack design in the drawings.

1 Claim, 8 Drawing Sheets
